UNITED STATES PATENT OFFICE

JOHN F. GRACE, OF KEARNY, NEW JERSEY, ASSIGNOR TO WORTHINGTON PUMP AND MACHINERY CORPORATION, A CORPORATION OF VIRGINIA

FEED WATER HEATER

Application filed August 20, 1920. Serial No. 404,932.

This invention relates especially to feed water heating apparatus of that class in which the cold water supply pump and the hot water feed pump deliver substantially fixed quantities of water, and which are provided with means for taking care of or compensating for the varying excess of water due to steam condensation, but certain features of the invention are applicable also to apparatus of other classes.

The especial object of the present invention is the provision of an improved feed water heating apparatus adapted especially for locomotive use, and which shall be efficient and durable under the exacting conditions of such service while of compact construction and especially of small vertical dimensions.

For a full understanding of the invention a detailed description of a locomotive feed water heating apparatus embodying all the features of the invention in their preferred form will now be given in connection with the accompanying drawings and the features forming the invention then specifically pointed out in the claims.

In the drawings—

Figure 1 is a sectional elevation of the complete unit;

Figures 2, 3, 4 and 5 are sections on, respectively, lines 2—2, 3—3, 4—4, and 5—5 of Fig. 1.

Referring to the drawings, A is the heat exchange chamber or heater proper receiving steam from steam connection 15 and cold water from atomizing spray nozzles 16, two or more preferably being used and three being shown, suitably secured in separable head 17 which covers the chamber A and is provided with a suitable passage 18 for delivery of cold water to the nozzles 16. I preferably provide, also, one or more small spring loaded spray valves 55, two being shown, so adjusted as to remain closed under normal pressure, but adapted to be forced open by any undue increase of pressure within the head 17.

Below the chamber A and forming a continuation thereof is the storage tank B to which the heated water passes for delivery to the hot feed pump. The chamber has a suit-

able downwardly contracting nozzle 19, directly below the spray nozzles and with an extended contracting discharge or tail pipe 20 by which the velocity of the water resulting from the spray nozzles and steam is maintained, this tube extending well down through the tank B and delivering to the upturned end of the feed water pump suction pipe 56 so as to conserve as far as possible the velocity of the water and thus reduce the suction head required and the necessary vertical dimensions of the heater.

At one side of the chamber A is located the cold water chamber C to which water is delivered by passage 21 connected at its lower end to the cold water supply pump discharge and preferably having its upper end extended well upward within the chamber C. In order to secure the removal of air from the cold water before its delivery to the spray nozzles 16 and to provide an air chamber for equalizing the flow from the cold water pump to the nozzles so as to secure a continuous spray and a cushioning of the liquid under the vibrations incident to locomotive use, the delivery passage 22 through which the water passes to passage 18 has its inlet well below the water level in chamber C. By this arrangement of the passages 21 and 22 the passage 22 is water sealed at its lower end, and the flow is such that the air separates from the water in chamber C and collects within the upper portion of the chamber to form an air cushion.

The excess water is compensated for by reducing the cold water delivery accordingly, and for this purpose a float control is used, and for reducing the effect of surging of the water incident to locomotive use, the float is not placed in the storage tank B, but in a separate small tank D connected to the storage tank by small top and bottom ports 23, 24, so that surging in the large tank does not affect the float, and the float is of a special construction hereafter described.

The chambers A, B, C and D may be formed in a single casting with a separable head, as shown, but it is to be understood that they may be formed in any other suitable

manner. At one side of this casting, and secured thereto so as to form a single unit therewith is the combined cold water supply and hot water pump E operated by the single direct-acting steam cylinder F. Pump E consists of a single cylinder 25 with the piston 26, driven by a piston rod 27, the upper end of the cylinder acting to supply cold water to the heater and the lower end to withdraw hot feed water from tank B and deliver the same. The hot water end of the pump has valve chest 28, shown as cast integral with and at one side of the cylinder 25, and provided with suction connection 29 having upturned pipe end 56, and with discharge connection 30 connected to discharge chamber 31 extending upward along the wall of tank B to form air chamber 33 and connecting with boiler supply connection 32 in the lower part of the chamber. The suction valve chamber is preferably extended and the total valve area much larger than that of the discharge valves, so as to provide for a free suction flow, which coacts with the water velocity to reduce the required head.

The upper end of the pump cylinder 25 which supplies cold water to the heater is provided with a valve chamber shown as formed by a casting 34 which slips over the upper end of the cylinder and is secured in any suitable manner to flange 35 on cylinder 25. This casting 34 provides a suction chamber 36 connected to cold water supply pipe 41 and having suction valves 37, a pulsation chamber 38, discharge valves 40 and discharge chamber 39 connected to the passage 21. The pump air chamber, preferably, is divided into two chambers 42, 43, so positioned as to allow the fireman to observe the piston rod 27 between them and note if the pump is working.

The steam cylinder F has the piston 44 connected to piston rod 27 for operating the pump piston and to a rod 45 connected by suitable levers to valve rod 46 for actuating the steam valve within valve chest 47. This valve gear is preferably protected by a cover 48. The exhaust from steam cylinder F is preferably discharged into the heating chamber A by pipe 53 and passage 54 in the heater casting for utilization.

The steam cylinder F and the pump E are preferably so formed as to allow the removal of the pistons 26 and 44 as a unit so that a set of spares may be substituted with a minimum of trouble and delay. For this purpose the pump E is provided with a split cylinder head 49 secured about piston rod 27 and the lower cylinder head 50 of steam cylinder F is provided with an opening of sufficient size to allow the passage of piston 26 therethrough. This opening is closed by a stuffing box 51 provided with a flange 52 which seats against the inner side of the lower cylinder head 50. By the removal of the

cover 48, the detachment of the valve gear from the rod 45, and the separation of the split cylinder head 49, the two pistons, their rods, and stuffing box 51, may be removed as a unit and a set of spares inserted in their place with a minimum of delay.

The pump construction is such that the ratio between the amounts of cold water delivered to and hot water removed from the heater remains constant, but due to condensation of the steam some excess of water may accumulate within the heater. A further feature of my invention is the provision of improved means for compensating for this excess of water. For this purpose, I provide a float, preferably in the form of a bucket 1 in the float chamber D which bucket is maintained full of water at all times by a pipe 2 secured in passage 3 connecting with chamber A. The bucket 1 is preferably slightly conical so as to prevent distortion by freezing and is pivotally mounted on bracket 4 on the chamber wall and is balanced, preferably by two counterweights 5, one on either side of the bracket 4. The float chamber D is provided with a passage 6 connecting with a passage 7 formed in casting 34 and at one side of the discharge chamber 39. A rod 8, pivotally secured to the counterbalanced bucket 1, passes through the passages 6 and 7 and is pivotally connected to a lever arm 9 on shaft 10 which passes through stuffing box 11 in the wall between passage 7 and the cold water suction pulsation chamber 38 and has a lever arm 12. The lever arm 12 is pivotally connected to a valve rod 13 which passes through the chamber 38 and is secured to a cylindrical valve 14 which slides within valve cylinder 15' provided with ports a connecting with ports b and c above and below the cylinder 15', these ports connecting, respectively, with the suction chamber 36 and pulsation chamber 38.

Upon an accumulation of excess water within the heater, the bucket 1 will be raised by the increased flotation effect of the water due to the raised water level aided by the counterweights 5, thereby acting through the connections to move the valve 14 inwardly, thereby opening the ports a to ports b, c and by-passing a portion of the cold water from the pulsation chamber 38 back to the suction chamber 36. This condition will continue until the water level has fallen to such an extent as to allow the float 1 to overcome the counterbalancing weights 4, when the valve 14 will be moved outwardly, closing the ports a and preventing further by-passing of cold supply water.

The operation of the construction will be understood from the drawings and the above description, with a brief statement. The cold water and steam enter chamber A, by, respectively, atomizing spray nozzles 16 and steam connection 15, where the steam is condensed, 130

and the heated water passes thence through nozzle 19 and tail pipe 20 to storage tank B and pipe 56 from which it is delivered by the lower end of pump E and pipe 30 to the boiler 5 through chamber 31 and pipe 32. The ratio between the quantities of water delivered to the heater and withdrawn therefrom by pump E remains constant. When there is such an increase in the quantity of steam and 10 consequently of water of condensation that the water level rises in float chamber D sufficiently to raise the counterweighted float 1 the valve 14 moves inward toward the pump E, so as to open the ports *a* to ports *b*, *c*, and 15 by-pass a part of the water from pulsation chamber 38 to suction chamber 36. This operation continues until the water within tanks B and D falls again and float 1 descends, thereby closing valve 14 for normal operation. 20 The pump E is so proportioned as to keep the feed water side of the pump full and the storage and float tanks filled to normal level, so that the float controls the supply only in accordance with the variable excess 25 from steam condensation.

It will be seen that the invention provides a very simple, compact and efficient feed water heating apparatus, adapted especially for locomotive use. The float chamber separate 30 from and at one side of the storage chamber is important, in that only the water necessary for float operation is carried in this chamber, and the splash and vibration effect upon the float largely reduced, so that the 35 regulation is more reliable and less subject to injury. The provision of an efficient apparatus of small vertical dimensions is aided, also, by the single pump cylinder, so that the 40 pump and steam cylinder may then be brought into very compact form vertically and a long pump stroke used, so that the size of the pump can be correspondingly reduced.

The enlarged suction valve area for the 45 hot water end of the pump, with the nozzle for maintaining the velocity of the feed water from the steam chamber to the pump, is important in reducing the head required, and this larger valve area for the hot suction than for the colder suction and delivery, secures efficiency and economy in pumping the 50 water at any temperature to which it may be heated. With the plunger rod on the cold water side, as shown and preferably used, the plunger rod may be made to compensate 55 for the different amounts of cold water and feed water and thus avoid liability to vapor binding and irregular action of the pump.

The use of the open float or bucket and its special mounting, is important in reducing 60 vibration, especially in locomotive use.

The compensating for excess water by reducing the supply, instead of returning the excess water to the supply pump, aids in securing economy, as there is no repumping 65 of the water. This feature is important,

also, in that the supply pump thus pumps nothing but cold water, so that there is less tendency to liability of vapor binding of the pump.

While the invention is especially applicable to locomotive feed water heating apparatus, and has been shown as thus applied, it will be understood that the invention is applicable also in connection with other feed water heating systems, and that the invention is not to be limited to the specific construction or arrangement of parts shown, as these may be varied widely within the invention as defined by the claims.

What is claimed is:

1. In a feed water heating apparatus, the combination with the heating chamber and storage tank, of pumping means comprising a supply pump portion and a feed water pump portion for delivering fixed quantities 25 of water to and from the heater, a float tank, a float in the float tank, and means controlled by the float to by-pass a portion of the supply from within the supply pump portion of the pumping means to the suction side thereof.

2. In a feed water heating apparatus, the combination with the heating chamber and storage tank, of pumping means comprising a supply pump portion and a feed water 25 pump portion for delivering fixed quantities of water to and from the heater, a float tank, connections between the storage and float tanks, a float in the float tank, a by-pass valve controlling a connection between the pulsation chamber and the suction chamber of the supply pump portion of the pumping means, and connections between the float and by-pass valve for by-passing a portion of the supply 30 from within the supply pump portion of the pumping means to the suction chamber thereof.

3. In a feed water heating apparatus, the combination with the heating chamber and storage tank, of pumping means comprising 35 a supply pump portion and a feed water pump portion for delivering fixed quantities of water to and from the heater, a float tank, connections between the storage and float tanks, an open float in said tank, connections 40 for maintaining said float full of water, means for balancing the float, and means controlled by the float to by-pass a portion of the supply from within the supply pump portion of the pumping means to the suction side 45 thereof.

4. In a feed water heating apparatus, the combination with the heating chamber and storage tank, of pumping means comprising a supply pump portion and a feed water 50 pump portion for delivering fixed quantities of water to and from the heater, a float tank, connections between the storage and float tanks, an open counterweight float pivoted in the float tank, connections for maintaining 55

the float full of water, a by-pass valve controlling a connection between the pulsation chamber and the suction chamber of the supply pump portion of the pumping means, and connections between the float and by-pass valve for by-passing a portion of the supply from within the supply pump portion of the pumping means to the suction side thereof.

5. In a feed water heating apparatus, the combination with the heating and storage chambers of pumping means comprising a supply pump portion and a feed water pump portion for delivering fixed quantities of water to and from the heater, a supply passage connecting the supply pump portion of the pumping means with the heating chamber, and means controlled by the water in the heater for reducing the discharge of the supply pump portion of the pumping means to the supply passage in case of an excess of water in the heater.

6. In a feed water heating apparatus the combination with a supply pump and passage for delivering water to the heater of a float 25 in said heater controlled by the water level in said heater, and means controlled by said float for reducing the discharge of the supply pump to said passage.

7. In a feed water heating apparatus, the combination with a supply pump and passage for delivering water to the heater, of a float controlled by the level of water in the heater, a by-pass valve in the pulsation chamber of the supply pump, and connections between the 35 float and the by-pass valve for reducing the discharge of the pump to said passage in accordance with the level of water in the heater.

8. In a feed water heating apparatus, the combination with the heating chamber, of a 40 single cylinder double acting supply and feed pump connected thereto with the upper end of said cylinder acting as a supply pump and the lower end as a feed pump, and means for reducing the discharge of the supply pump to its heater connection in accordance with the level of water in the heater.

9. In a feed water heating apparatus, the combination with the heating chamber and storage tank, of a single cylinder double acting supply and feed pump connected thereto with the upper end of the pump acting as a supply pump and the lower end as a feed pump, a float tank separate from the storage tank, a float in the float tank, and means operated by the float for reducing the discharge of the supply pump to its heater connection in accordance with the level of the water in the heater.

10. In a feed water heating apparatus, the combination with the heating chamber, of one or more spray nozzles for the water supply, a feed pump, and connections between the heating chamber and pump acting to maintain the velocity imparted to the water 65 in the heating chamber and reduce the head

required for opening the suction valves of the feed pump.

11. In a feed water heating apparatus, the combination with the heating chamber, of one or more spray nozzles for the water supply, a feed pump, and a contracting tail pipe 70 connecting said heating chamber and feed pump to maintain the velocity of the water from said heating chamber.

12. In a feed water heating apparatus, the combination with the heating chamber, of one or more spray nozzles for the water supply, a single cylinder double acting feed pump having its upper end acting as a supply pump and its lower end as a feed pump, and a contracting tail pipe 80 connecting said heating chamber and feed pump to maintain the velocity of the water from said heating chamber.

13. In a feed water heating apparatus, the combination with the heating chamber, of one or more spray nozzles for the water supply, a feed pump, a contracting tail pipe connecting said heating chamber and feed pump to maintain the velocity of the water from 90 said heating chamber, and a suction chamber and suction valves on said feed pump having an enlarged area for reducing the head required.

14. The combination with the heating chamber A and its steam and cold water inlets, of storage tank B, contracting throat 19 and tail pipe 20 within the storage tank, and a feed pump receiving its supply from the tail pipe.

15. The combination with the heating chamber A and its steam and cold water inlets, of contracting throat 19 and tail pipe 20, a feed pump, and a suction pipe 56 on said pump in line with and adjacent to the lower end of said tail pipe.

16. An open type feed water heater comprising a heating vessel, means for admitting steam thereto, separate means for admitting cold water to said vessel, a hot water outlet from said vessel, a single pump cylinder and piston having a fixed ratio between the cold and hot water displacements, valve-controlled inlet means and outlet means for cold water at the upper end of said cylinder, a valve-controlled inlet for hot water at the lower end of the same cylinder, a valve-controlled outlet for hot water from the lower end of said cylinder, and means controlled by a slight increase in the water level in said vessel for decreasing the rate of supply of cold water to said vessel.

In testimony whereof I have hereunto set my hand.

JOHN F. GRACE. 125
